A. MEISSNER

SENDING ARRANGEMENT

Filed Sept. 3, 1921

Inventor
ALEXANDER MEISSNER

By his Attorney

Dr. J. Adams

UNITED STATES PATENT OFFICE.

ALEXANDER MEISSNER, OF BERLIN, GERMANY, ASSIGNOR TO GESELLSCHAFT FÜR DRAHTLOSE TELEGRAPHIE M. B. H. HALLESCHES, OF BERLIN, GERMANY, A CORPORATION OF GERMANY.

SENDING ARRANGEMENT.

Application filed September 3, 1921. Serial No. 498,420.

(GRANTED UNDER THE PROVISIONS OF THE ACT OF MARCH 3, 1921, 41 STAT. L., 1313.)

To all whom it may concern:

Be it known that I, ALEXANDER MEISSNER, citizen of the German Republic, residing at Berlin, Germany, have invented certain new and useful Improvements in Sending Arrangements (for which I have filed applications as follows: Germany, Pat. No. 333,297, filed Oct. 24, 1918; Argentina, register No. 21 333/236, filed July 20, 1920; 5 Brazil, register No. 172 38, filed July 10, 1920; Chile, filed Sept. 23, 1920; Denmark, register No. 3423/19, filed Dec. 18, 1919; Netherlands, register No. 14287, filed March 13, 1920; Japan, register No. 58307, filed 10 July 1, 1920; Norway, register No. 18896/19, filed Dec. 31, 1919; Austria, register No. A 3870/19, filed Dec. 23, 1919; Peru, filed Oct. 29, 1920; Sweden, register No. 50290/19, filed 15 Nov. 25, 1919; Spain, Patent No. 72,216; 20 Czechoslovakia, register No. 4766/20, filed June 25, 1920), of which the following is a specification.

The invention relates to sender arrangements for high frequency oscillations as 25 used in wireless telegraphy, and its main object is to radiate from the antenna the ground wave and to prevent the entrance of the over-waves into the antenna. In accordance with the present invention, a short- 30 circuit tuned to the over-waves is connected in parallel with the high frequency generator or with the transformer associated with the high frequency generator. Such short-circuit presents an infinite resistance against 35 the ground waves, but short circuits the over-waves.

The drawing shows an exemplification of the arrangement.

T is a secondary winding of the trans- 40 former connected with the high frequency generator. If a cathode tube is used for generating oscillations, instead of the trans- 45 former, the tube with its coupling element may be connected in the circuit. The sec- ondary winding of the transformer is

grounded at B, and is connected at A with antenna S. In accordance with the invention, a short circuit K is provided ahead of the antenna loading inductance L, and comprises an inductance J and a capacity C. 50 By means of the two values, the short circuit K is tuned to the over-wave and serves, therefore as a shunt path for the over-waves but presents an infinitely high resistance against the ground waves. 55

I claim:

1. A sending arrangement for wireless telegraphy and telephony comprising a grounded antenna and means for preventing radiation from the antenna of harmonics of the fundamental frequency of the arrangement, said means comprising a grounded circuit arranged in parallel with the grounded portion of the antenna and tuned to the harmonics. 65

2. A sending arrangement for wireless telegraphy and telephony comprising a grounded antenna, and means for preventing radiation from the antenna of a harmonic of the fundamental frequency of the arrangement, said means comprising a grounded circuit arranged in parallel with the grounded portion of the antenna, and said circuit including an inductance and capacity in series and being tuned to the harmonic so as to constitute therefor a short-circuit to ground. 75

3. A sending arrangement for wireless telegraphy and telephony comprising an antenna, a loading inductance in the antenna, and means for preventing radiation from the antenna of a harmonic of the fundamental frequency of the arrangement, said means comprising a grounded circuit connected to the antenna between the loading inductance and ground in parallel with the grounded portion of the antenna and tuned to the harmonic. 80

In testimony whereof I affix the signature.
ALEXANDER MEISSNER.
